UNITED STATES PATENT OFFICE

2,519,677

FOOT MEASURING APPLIANCE

James Edwin Mackay, Street, England, assignor
to C. & J. Clark Limited, Street, England, a
British company

Application November 16, 1948, Serial No. 60,240

4 Claims. (CL 33—3)

1

This invention relates to an improved foot measuring appliance, primarily intended for use by retailers of footwear which is available in stock sizes and fittings.

The present invention relates more particularly to a foot measuring appliance of the kind which comprises a base, a heel stop carried by said base, a second stop slideable relative to the heel stop for contacting the toe end of the foot and indicating the required footwear size on a scale disposed on said base, and an intermediately disposed member swivelly adjustable to enable a measuring tape carried thereby to be passed over the widest part of the foot for gauging the girth dimension thereof.

The main object of the invention is to provide an improved appliance of the kind above specified which can be used speedily and easily for determining those basic measurements of the foot which suffice to enable the retailer to decide the size and fitting of footwear required, that is, the overall length of the foot, the girth dimension of the foot at its widest part and the heel-to-ball measurement of the foot. The length of the foot is generally expressed in terms of a number, well known to the public as the size of the footwear, and this "size" can be directly indicated on a scale mounted on the appliance.

The term "fitting" is generally employed to designate the width of the footwear required and to ensure correctly fitting footwear. A range of widths, for example four different widths, are generally provided for each "size" of footwear. The effective width of the foot is gauged in appliances of the kind above specified by measuring the girth of the foot at its widest point, viz: on a line which is inclined in relation to the longitudinal plane in which the foot normally lies, and this inclined line may be considered as passing through the metatarsal joints of the "big" toe and the "little" toe.

In foot measuring appliances of the kind set forth the foot being measured has been supported by means of a heel pad raised above the surface of a base and also at its widest part by means of a separate disc or similar plate slideably, and, in some cases, swivelly movable upon the surface of the base, the measuring tape passing between the base and the movable disc or plate.

Another object of the present invention is to provide a foot measuring appliance of simplified construction and this object is achieved by supporting the foot being measured both below the heel and below the widest part of the foot by

2

means of a single foot-supporting bar, beneath which a tape-carrying member is freely slideably and swivelly mounted.

A further object of the invention is to provide improved means whereby the girth of the foot may be readily and accurately determined. The gauging measurement thus obtained, which is preferably expressed in terms of some arbitrary units or standards instead of a direct linear measurement, may be compared with a series of corresponding units set out alongside of the "size" of the footwear directly indicated on the scale by the means provided for gauging the overall length of the foot.

15 A still further object of the invention is to provide an appliance of the character above referred to which is of compact form and adapted for use on the existing shop furniture comprising a platform for the foot of the person being fitted to rest upon, this platform being frequently constructed on an integral part of the stool for the shop assistant.

A practical embodiment of the invention is shown, by way of example, in the accompanying drawings, wherein:

Figures 1 and 2 are front and rear perspective views respectively of the appliance.

Figure 3 is a plan view of the complete appliance,

Figure 4 is a longitudinal sectional elevation on line IV, IV of Figure 3, and

Figure 5 is a cross section on line V, V of Figure 3, drawn to a larger scale.

In the construction shown, the foot of the person being fitted is supported longitudinally on a flat bar 1 mounted lengthwise in bridge-like manner upon a base 2 of elongated frame form so as to span the frame opening 3, the relative widths of the bar 1 and frame opening 3 being such as to leave slots 4 on opposite longitudinal sides of the bar 1. At one end of the bar 1 is a fixed stop plate 5 which engages and supports the back of the heel, whilst a second stop 6 is mounted for sliding movement over the top face of the bar 1. The stop 6 is adapted to be slid along the bar 1 into contact with the longest toe and is retained on the bar 1 by means of a cruciform member 7 which passes under the bar 1 with its longitudinal limb engaged in a groove 8 formed in the underside of the bar 1. The cruciform member 7 is attached through its transverse limb by screws 9 to lugs 10 which depend down from the stop 6 on opposite longitudinal sides of the bar 1. The toe stop 6 is of wedge shape in longi-

50 55

tudinal cross section and the thin edge of the wedge is adapted to indicate directly the "size" of the footwear required for the length of foot gauged between the stops 5 and 6 on a scale card 11 stationed in a shallow recess 12 provided in the top face of the foot-supporting bar 1. The numerals indicating the size of footwear are given in the first column of the scale card 11, the remaining four columns give alongside of each size numeral a series of numbers corresponding to those on the foot-width measuring tape as referred to later. Markings corresponding to those at the head of the columns on the scale card 11 may be repeated on the sloping front face of the wedge-shaped toe stop 6 to facilitate reading of the card 11 as the toe stop 6 is moved thereover.

Intermediately of the fixed heel stop 5 and the slidably adjustable toe stop 6 is a block 13 comprising a pair of side flanges 14 and a dropped centre part 15. The block 13 is supported by the sliding of the side flanges 14 along the marginal portions of the base 2 which flank the slots 4. The floor of the centre part of the block 13 is disposed below the bar 1 and the thickness of the side flanges 14 of the block 13 is such that their upper faces do not project up above the top face of the bar 1 on which the foot is supported. The cheeks or side walls 16 of the sunken centre part 15 of block 13 are radioused or chamfered as shown so that the block 13 is free to swivel under the bar 1 and thus dispose a measuring tape 17 in the appropriate diagonal or inclined position to embrace the foot at its widest part, that is on a line extending through the metatarsal joints of the big toe and little toe. The tape 17 is threaded through the slots 4 above the floor of the centre part 15 of block 13 and extends outwardly and upwardly on opposite sides of the bar 1 through aligned recesses 18 which open into the cheeks or side walls 16. One end of the tape 17 is provided with a loop 19 through which the other end of the tape may be threaded so as to strap down the foot lightly on to the bar 1. The inside face of the tape 17 carries a series of numerals and the numeral which can just be seen where the free end of the tape 17 doubles back over the bar of the loop 19 is sought for in one of the four columns opposite to the "size" numeral indicated by thin front edge of the toe stop 6 in the first column of the scale card 11. The reference at the head of the column where the tape numeral being sought for is found designates the "fitting" required. If the toe stop 6 indicates, for example, that a "size 8" shoe is required for the foot being measured, whilst the tape 17 reveals the numeral "28" which is to be found in the third column of the scale card 11 in line with the indicated size numeral "8," the reference "A" at the head of this third column designates the "fitting" of footwear required. The scale card 11 is detachably accommodated in the recess 12 provided on the bar 1 so as to be interchangeable with other similar cards covering stock footwear sizes and fittings for men's, women's and children's shoes. The side flanges 14 of the block 13 are provided with chamfered edges 20 which are adapted, when the block 13 is inclined one way or the other according to whether the right foot or the left foot is being measured, to indicate a marking on one or other of the similar side scales 21 accommodated in shallow recesses 22 in the top face of the base 2. This marking affords an indication of the heel-to-ball measurement of the foot and is also taken into account

when deciding which standard fitting of shoe will meet the customer's needs.

I claim:

1. A foot measuring appliance comprising an elongated base bearing two side scales extending parallel one to the other and longitudinally of said base for indicating heel to ball measurement of a foot, a longitudinal foot - supporting bar fixedly mounted above said base and between the said side scales, a fixed heel stop at one end of said supporting bar, a toe stop slidable on said supporting bar relative to the fixed heel stop, a size indicating scale on said supporting bar, said toe stop directly indicating on said size indicating scale on said foot-supporting bar the shoe size required for the length of foot measured, a longitudinally slidable block disposed intermediately of said heel and toe stops and mounted to swivel under said foot-supporting bar, said block having chamfered portions on each side edge thereof adapted to indicate on said side scales according to the degree of swivelling of said block, the shoe fitting required for heel to ball fitting, and a measuring tape carried by said slidable swivel block and threaded under said foot-supporting bar with its free ends engageable to strap over the widest part of the foot resting on said longitudinal supporting bar.

2. A foot measuring appliance comprising in combination, a base of elongated frame form having an elongated opening, two longitudinally extending and parallel scales on said frame form, one on each side member of the frame-like base for indicating heel to ball measurement of a foot; a longitudinal foot-supporting bar spanning the length of said elongated opening in bridge-like manner and providing a slot along each longitudinal side of said bar; a fixed heel stop at one end of said foot supporting bar, a toe stop slidable on said supporting bar relative to said fixed heel stop, a shoe size indicating scale on top of said foot supporting bar bearing the shoe size required for the length of foot measured, said toe stop directly indicating on said size scale; a longitudinally slidable block disposed intermediately of said heel stop and toe stop, side flanges on said block slidably suspending said block on the margins of said slots flanking the bridge-like bar, said block having a sunken center part accommodated within the frame opening of said base connected with said side flanges through said slots, said block being mounted to swivel under said foot-supporting bar, said block having chamfered edge portions thereon adapted to indicate, according to the degree of swivelling of said block, on one or other of said side scales the shoe fitting required for heel to ball fitting, and a measuring tape carried by said slidably swivel block and threaded under said foot-supporting bar with its free ends engageable to strap over the widest part of the foot resting on said longitudinal supporting bar.

3. A foot measuring appliance according to claim 2, and wherein the side walls of said sunken center part of said block are bevelled to permit the block to swivel in relation to said bar, said side flanges of said block having aligned recesses therein which serve to guide the loop of the measuring tape under said foot-supporting bar.

4. A foot measuring appliance according to claim 2, wherein the measuring tape carries a series of numerals which correspond to columns of numerals on said shoe size indicating scale to indicate the fitting of footwear required for

the girth of foot measured, these columns of numerals on said shoe size indicating scale being related to the appropriate size of footwear required for the length of the measured foot.
